COMPENSATOR FOR BRUSH-RESISTANCE VOLTAGE DROP IN MOTOR-CONTROL SYSTEMS

Application filed April 5, 1928, Serial No. 267,534, and in Germany April 12, 1927.

The invention relates to a connection adapted to keep constant the minimum number of revolutions of a continuous current motor operating according to the Ward Leonard system.

When a continuous current motor is loaded with a determined turning moment, its armature, in order to rotate, must be put at least under that voltage which corresponds to the product of the armature resistance and the required strength of current, disregarding the losses of voltage in the supply wires and the like. If e. g. the required current load for a determined turning moment is 100 a. and the resistance of the armature winding is 0.1 ohm, then the minimum voltage at which the armature is capable of being rotated is $100 \cdot 0.1 = 10$ v. With this amount of voltage the motor runs at the minimum number of revolutions at which it can rotate with the given current load. Should the required current strength vary even in the slightest degree, the number of revolutions of the armature will vary, that is, when the required strength exceeds 100 a., the armature stops at once, unless at the same time the voltage supplied is increased in correspondence with the increased loss of voltage in the supply wires and the like. The loss of voltage in the supply wires is proportional to the product of the strength of current and the resistance of these wires; the resistance is to be regarded as constant, if the heating is neglected.

A constantly varying and absolutely uncontrollable resistance, however, is to be found in the brush contact resistance, which varies constantly according to the specific current load, to the contact pressure of the brushes, the number of revolutions and mode of running of the commutators and to the nature of their contact surface, to the quality and hardness of the brushes and, finally, to the conditions of commutation.

My invention has for its object to so regulate automatically the voltage supplied to the motor in accordance with the degree of brush contact resistance prevailing at any instant, that the motor runs at its minimum number of revolutions without stopping upon

variation in the load. According to the invention this object is obtained with the aid of auxiliary brushes provided on the terminals of the generator and the motor, the auxiliary brushes of like polarity being connected to the ends of the same auxiliary regulating circuit or winding, there being two such auxiliary regulating circuits or windings each interposed between like terminals of the motor and of the generator. 55

A wiring diagram illustrating the arrangement forming the subject-matter of my invention is shown in the drawing which accompanies and forms part of this specification. 60

On each terminal of the generator G and motor M is arranged an auxiliary brush b_1 , b_2 , b_3 , b_4 insulated from the main brushes B_1 , B_2 , B_3 , B_4 , the auxiliary brushes of equal polarity being connected with the ends of one of two exciting windings n_1 and n_2 of the generator G, while brushes of unlike polarity are connected with different exciting windings, said windings forming part of auxiliary regulating circuits i_1 and i_2 respectively which are interposed between like terminals of the motor and of the generator. The current flowing in the circuit i_1 and i_2 , respectively, of the auxiliary brushes b_1 , b_3 and b_2 , b_4 respectively is proportional to the drop 70 of voltage between that commutator segment of the generator and of the motor with which the main brushes are in contact at that particular instant of operation. The resistance of this circuit is composed of the resistance 75 of the supply wire l_1 and l_2 , respectively, and of the contact resistance of the main brushes B_1 , B_3 and B_2 , B_4 , respectively. The strength of the current flowing in the auxiliary regulating circuits i_1 and i_2 is independent of the 80 terminal voltage of the generator G. Therefore the exciting windings n_1 , n_2 act correctly at any speed of the motor, that is, on the entire regulating range of the motor as well as also with reversed direction of rotation of 85 the latter, that is, they increase the voltage by permanently exciting additionally the generator in the direction of the separate exciting winding N. When the load increases, 90 then the strength of the current flowing in 95

100

the circuits i_1 and i_2 increases too and there-
with the excitation of the generator and con-
sequently the voltage supplied to the motor by
the generator increases proportionally to the
loss of voltage arising in the entire circuit,
this loss being compensated for in this way
if the windings n_1 and n_2 are suitably dimen-
sioned. The speed of the motor is thus kept
practically constant, as long as the char-
acteristic of the generator runs rectilinearly.

- 10 10 Instead of the regulating exciting wind-
ings n_1 , n_2 controlling means, as relays, con-
tact amperemeters and the like may be in-
serted in the circuit of the auxiliary brushes,
15 which means in their turn regulate special
compensating windings or the separate ex-
citing winding N of the generator G .

What I claim, is:—

1. In an electric plant a generator and a
20 continuous current motor adapted to be
driven by it according to the Ward Leonard
system, auxiliary regulating circuits between
the terminals of said generator and said mo-
tor, said circuits including auxiliary brushes
25 on the commutators of said generator and
said motor, the brushes of like polarity be-
ing connected to the same auxiliary regulat-
ing circuit while brushes of opposite polarity
are connected with different auxiliary regu-
30 lating circuits, and means included in said
auxiliary circuits for regulating the voltage
supplied to said motor in accordance with the
varying brush contact resistances of both the
said motor and said generator.

- 35 2. In an electric plant a generator and a
continuous current motor adapted to be
driven by it according to the Ward Leonard
system, auxiliary regulating circuits between
the terminals of said generator and said mo-
40 tor, an exciting winding in each of said regu-
lating circuits, and auxiliary brushes in-
cluded in said regulating circuits and engag-
ing the commutators of said generator and
45 said motor respectively, the brushes of like
polarity being connected to the ends of the
same exciting winding, while brushes of un-
like polarity are connected with different ex-
citing windings.

In testimony whereof I have affixed my sig-
nature.

HERMANN SUNDHAUSSEN.
